UNITED STATES PATENT OFFICE.

JOHN L. HAPPY, OF CHICAGO, ILLINOIS.

COMBINATION TABLE.

1,427,208.

Specification of Letters Patent. Patented Aug. 29, 1922.

Application filed October 30, 1918. Serial No. 260,245.

To all whom it may concern:

Be it known that I, JOHN L. HAPPY, a citizen of the United States, residing at Chicago, in the county of Cook and State of Illinois, have invented a certain new and useful Improvement in Combination Tables, of which the following is a specification.

My invention relates to an improved form of combination table designed for kitchen use and consisting of an ironing board, clothes rack and quilting frame forming part of the table structure and designed for use therewith, the parts being so constructed that when not in use they are contained in a compartment of the table immediately below the top thereof. In this condition the table is serviceable for the purposes to which a kitchen table is ordinarily put.

My invention will be best understood by reference to the accompanying drawings, showing a preferred embodiment thereof in which Fig. 1 shows the table in plan view with the ironing board in position for use and ends of the quilting bars attached in the position in which they are used,

Fig. 2 is an end view of the table taken from the opposite end to the end supporting the clothes rack,

Fig. 3 is an end view of the parts shown in Fig. 1, this view being taken from the end of the table supporting the clothes rack,

Fig. 4 is a side view of the upper part of the table showing the door for closing the compartment for containing the several parts when not in use,

Fig. 5 shows the table in plan view with the quilting bars and their support in position for use,

Fig. 6 is an end view of the table and parts shown in Fig. 5,

Fig. 7 is a side elevation of the upper part of the devices to support the outer end of the quilting bars when in use,

Fig. 8 is a detail view of the fixture employed on the table to support the quilting bars and

Fig. 9 is a detail view of a modified device for connecting the sections of the quilting bars together.

Similar numerals refer to similar parts throughout the several views.

As shown in Figs. 1, 2 and 3, the table consists of the top 10 supported on legs 11 which support at their upper ends immedi-

ately beneath the table top a compartment 55 12 enclosed by side walls 13, end walls 14 and a bottom 15 to contain the ironing board, quilting bars and clothes rack when not in use. The legs 11 may be secured to the compartment 12 and the table top in 60 a manner well known in the art so as to be readily removable and constitute a so-called "knock down" construction for shipping purposes.

One end wall 14 of the compartment 12 65 is slotted at its upper edge as shown at 16 to receive the bars 17 of the clothes rack, which bars rest immediately below the table top and are retained in place by said slot and a casing 18 secured to the under side of 70 the table top, which casing also protects the bars from interference with the parts contained in the compartment 12. The bars 17 may be drawn out longitudinally from the casing 18 and spread from each other to 75 conveniently support articles as may be desired. Each bar carries at its inner end a downwardly projecting pin 19 to prevent entirely withdrawing the bars from the table.

At the other end of the table corner brackets 20 and 21 are secured between the end and side walls which serve to hold the adjacent leg 11 in place and also constitute the end supports of a vertical rod 22 upon which 85 a bracket 23 is mounted to swing and move vertically. The outer end of the bracket 23 is pivotally connected with a stud 24 rigidly secured to the under side of one end of the ironing board 25. Also secured to the under side of the ironing board are a leg construction 26 and a brace 27, which when 90 they occupy the position indicated in Fig. 3 serve to support the outer end of the ironing board in horizontal position. Leg 26 95 and brace 24 are connected with the board by hinges 28 and 29 respectively, so that when it is desired to fold up the ironing board the brace 27 is first folded against the bottom of the board and the leg 26 is then 100 folded against the bottom of the board holding the brace in its folded position and the leg is held in its folded position by means of a hook 30 carried by the under surface of the board engaging a pin or stud 31 carried by the leg 26. The inner end of the board in its working position is secured to the table top 10 by a catch 32 so as to pre-

vent vertical motion of the ironing board at its inner end and keep the upper surface of the board in the same horizontal plane as the table top, and also to prevent motion of the ironing board away from the table top. I find that a catch of the kind ordinarily employed to fasten window sashes answers admirably for this purpose. In moving the ironing board to its closed position the catch 32 is released after holding the leg and brace in the manner described and the bracket 23 is permitted to move downwards on the rod 22 until it rests on the lower bracket 21, in which position, after opening the door 33, the board may be swung on the bracket into the compartment 12 below the casing 18. The door 33 is hinged to the corresponding side wall 13 of the compartment 12 and held in closed position by any suitable form of catch 34. The end wall 14 of the compartment 12 adjacent the ironing board support is provided with an extension 35 which has a door 36 mounted on a spring hinge 37 and held in closed condition by a button 38 when the ironing board is in place in the table. In moving the ironing board from the table or into the table the button 38 is turned to free the door 36 and permit the corners of the inner end of the ironing board to move the door 36 outwards sufficiently to clear said corners. The proportions are preferably such that when the ironing board is in place in the compartment 12 it extends from the inner surface of the end wall 14 remote from the door 36 to the inner surface of the door 36, as a result of which, turning the button 38 to hold the door 36 in its closed position holds the ironing board against displacement in the compartment 12.

As shown in Figs. 5 to 8 inclusive, the table top 10 has connected to its under surface on the edge opposite the door 33 two brackets 39 extending downwardly from the table top, each bracket being constructed as indicated in Fig. 8 with a clearance hole 40 through its downwardly extending portion, from the lower side of which a slot 41 extends a sufficient distance to form a seat for a pin 42 carried by the inner end of each quilting bar 43. Each quilting bar 43 is made of a length sufficient to handle quilts of regular size in the making thereof and to facilitate storing the bars when not in use in the compartment 12 each bar is preferably made in two sections hinged to each other at 44, so that when desired the sections may be folded one upon the other for storing the quilting bars. When in use each quilting bar is provided with a sleeve 45 which may be slid over the joint between the sections thereof to hold said sections rigidly in line with each other, said sleeve being preferably in the form of a metal tube. The outer end of each quilting bar is of reduced

diameter to enter holes therefor as indicated at 46 through the upper ends of legs 47 and cross piece 48 employed to support the outer ends of said quilting bars in horizontal position when in use. The legs 47 are pivotally connected to the cross piece 48 at 49, and in any desired manner, as by means of screws, so that when the quilting bars are in place in the openings 46 the legs 47 cannot be rotated relatively to the cross piece 48. 75 75

The cross piece 48 is preferably slotted through the holes 46 formed in it and provided with clamp screws 50 for clamping the end portions of the quilting bars in any desired position which provides a convenient means for rolling the quilt upon the bars and holding it in any desired position while work is being done upon it. 80

When it is desired to store the quilting bars the clamping screws 50 are released, 85 the legs 47 are removed from the ends of the bars, the bars are removed from the brackets 39 and the sleeves 45 are moved to free the sections of the quilting bars from each other in which condition the bars are 90 folded and are then of a length to be placed in the compartment 12 below the ironing board. To facilitate storing the legs 47 the cross piece 48 is in two sections hinged together at 51 and provided with a locking 95 hook 52 to hold said sections in line with each other when the legs are in use. To store the legs the hook 52 is released, the legs 47 are swung into line with the cross piece 48 and the cross piece is folded by 100 means of the hinge 51 in which condition the parts may be placed for storage in the bottom part of the compartment 12.

As a result of the construction described it will appear that I have provided a table 105 which is not only useful for ordinary purposes, but which serves as a support and housing for the bars of the clothes rack, which also serves as a support and housing for the ironing board and which also serves 110 as a support and housing for the quilting bars, thus affording a wide range of usefulness and a compact construction when the various devices are not required and it is desired to use the table for its ordinary 115 purposes.

If preferred the quilting bars may be secured together by a modified construction as shown in Fig. 9 in which the sections of the bar 43^a are provided with holes 53 through them which rigidly support nuts 54 centrally in said sections to receive the threaded ends of the bolt 55. With this construction when it is desired to connect the sections together the bolt 55 is inserted in holes therefor in the adjacent ends of the sections and the sections are turned relatively to each other to engage the bolt with the nuts 54, which is continued until the sections are tightly clamped together by means of the 125 130 135

bolt, and when it is desired to disconnect the sections from each other the sections are turned relatively to each other in the reverse direction to disconnect the bolt 55 from one 5 of the nuts.

While I have shown my invention in the particular embodiments above described, I do not, however, limit myself to this exact construction, as I may employ equivalents 10 thereof known to the art at the time of the filing of this application without departing from the scope of the appended claims.

For example: While it is desired to construct the brackets 20 and 21 and the brackets 15 39 of metal, they need not be constructed of this material as my invention is realized if other material is employed which will secure the same result.

What I claim is:

20 1. In a device of the class described, the combination of a table, an ironing board, a pivot secured to said table under its top for supporting said board, a leg for supporting the outer end of said board, whereby said 25 board may be swung under the top of said table when not in use or to extend from said table when in use as desired, and a brace for said leg, said brace and leg being hinged to said board to fold against the same when 30 not in use, said table having a closed compartment under its top for containing said board when not in use, and said compartment having a door at one end opening to permit motion of said board to and from 35 said compartment, said board being of a length to fit between said door and the opposite end of said compartment, and a device for holding said door in its closed position.

2. In a device of the class described, the 40 combination of a table, an ironing board, a pivot secured to said table under its top for supporting said board, a leg for supporting the outer end of said board, whereby said 45 board may be swung under the top of said table when not in use or to extend from said table when in use as desired, and a bracket mounted at one end on said pivot and piv-

otally connected at its other end to said board.

3. In a device of the class described, the 50 combination of a table, an ironing board, a pivot secured to said table under its top for supporting said board, a leg for supporting the outer end of said board, whereby said 55 board may be swung under the top of said table when not in use or to extend from said table when in use as desired, a bracket mounted at one end on said pivot and piv- 60 tally connected at its other end to said board, said pivot permitting vertical motion 65 of said board for use into the plane of said table top, and a catch for holding said board to the table in said plane, said table having a closed compartment under its top for containing said board when not in use, and said 70 compartment having a door at one end opening to permit motion of said board to and from said compartment, said board being of a length to fit between said door and the opposite end of said compartment, and a 75 device for holding said door in its closed position.

4. In a device of the class described, the combination of a table, a vertical pivot rod under the table top and carried by the table, 75 an ironing board, an arm extending from said board to said pivot rod to turn on said rod and move vertically thereon, whereby said ironing board may be turned to lie below the table top when not in use or project from said table top in the plane thereof when in use, mechanism for holding said ironing board in the plane of said table top with said arm in its upper position on said 80 rod, and a pivotal connection between said rod, and a pivotal connection between said 85 arm and said ironing board permitting said board to lie longitudinally of said table top when not in use and extend transversely of said table top when in use.

In witness whereof, I hereunto subscribe 90 my name this 21st day of October, A. D. 1918.

JOHN L. HAPPY.
